(57) **CLAIM**

The ornamental design for a goods display tray, as shown and described.

DESCRIPTION

FIG. 1 is a top and right front perspective view of a goods display tray, showing my new design;

FIG. 2 is a right side elevational view thereof, the left side elevational view being a mirror image of the side view shown;

FIG. 3 is a front elevational view thereof, the rear elevational view being a mirror image of the front view shown;

FIG. 4 is a top plan view thereof;

FIG. 5 is a bottom plan view thereof;

FIG. 6 is a cross-section view taken along line A—A of FIG. 4; and,

FIG. 7 is a top and right perspective view thereof in a state of use when holding articles for display.

The broken line showing of the articles for display in FIG. 7 is for illustrative purposes only and forms no part of the claimed design.
